(57) CLAIM

The ornamental design for a key for a lock, as shown and described.

DESCRIPTION

FIG. 1 is a front view of a key for a lock showing my new design;

FIG. 2 is a plan view thereof;

FIG. 3 is a right side view thereof;

FIG. 4 is a rear view thereof;

FIG. 5 is a bottom view thereof;

FIG. 6 is a left side view thereof;

FIG. 7 is an enlarged cross-sectional view thereof taken on section line VII-VII in FIG. 1; and,

FIG. 8 is an enlarged cross-sectional view thereof taken on section line VIII-VIII in FIG. 1.
